REUBEN L. WRIGHT, OF CLEVELAND, OHIO, ASSIGNOR TO THE ELECTRIC CONTROLLER AND SUPPLY COMPANY, OF CLEVELAND, OHIO, A CORPORATION OF OHIO.

CONTROLLING SYSTEM FOR LIFTING-MAGNETS.

No. 895,135.

Specification of Letters Patent.

Patented Aug. 4, 1908.

Application filed April 10, 1908. Serial No. 426,207.

To all whom it may concern:

Be it known that I, REUBEN L. WRIGHT, a citizen of the United States, residing at Cleveland, in the county of Cuyahoga and State of Ohio, have invented or discovered new and useful Improvements in Controlling Systems for Lifting-Magnets, of which the following is a specification.

My invention relates to a new and improved system of control for lifting magnets.

As far as I know, all lifting magnets have been shunt wound and connected directly across the supply mains, or with permanent resistances in series with their windings. Under these conditions, the current which flows through the magnet depends on the resistance of the magnet circuit and the voltage of the mains where the magnet is connected. When lifting magnets are attached to electric hoists or cranes, the voltage of the supply mains at the crane or hoist is at its lowest value just as the magnet is being hoisted away from the pile of magnetic material, on which it is working. This is due principally to two causes: First, more current is required to accelerate the hoisting mechanism, the magnet and the load than is required after the load has left the pile; and second, with an excited lifting magnet resting on a pile of magnetic material, the crane or hoist must exert a greater pull to separate the magnet and its load from the pile than to hoist the magnet and load after the load has been lifted from the pile. This increased current causes an increased drop in voltage at the crane and thus a drop of current in the magnet circuit.

I have observed that the lifting capacity of a magnet is proportional to the current flowing through its winding and that after a load of magnetic material has been lifted away from the pile, this current may be materially reduced without causing the magnet to drop its load. It is therefore seen that a shunt magnet has a minimum current through its winding just at the time that a maximum current is desirable and it has a maximum current when it is desirable to have a minimum current. Such a magnet therefore loses in lifting capacity, and its winding is subjected to greater heating than is desirable.

My invention overcomes these objections and supplies means whereby a greater current may be caused to flow through the mag-

net winding just as the magnet and load are leaving the pile, and later to automatically reduce this current and the consequent unnecessary heating of the magnet winding. This allows a magnet to lift a greater load with the same heating of windings or the same load with less heating.

My invention is illustrated in the accompanying sheet of drawings which shows a diagrammatic view thereof.

On the drawing, S is a double-pole knife switch which connects the motor and magnet circuits to a suitable source of electrical energy. From the positive pole of this switch current is led by the wire 1 to the winding o^4 of the relay O, from which winding the current passes through the motor controller switch C when closed and through the armature A and its field F to the negative pole of the switch S.

The wire 2 connects the contact b' of the magnet controller B to the wire 1 which is connected to the positive side of the switch S.

The movable arm s^4 of the switch S' is connected by the wire 3 to the contact b^2 of said controller B, whose arm b^4 carries the brush b^3 arranged to bridge the contacts b' and b^2 when the controller arm b^4 is swung to the left.

The arm s^4 carries the contact s^2 , which cooperates with the fixed contact s^1 , to which one end of the magnet winding M is connected, the remaining end of the magnet winding being connected by the wire 4 to the negative pole of the switch S.

The resistance R is in a shunt between the contacts s^1 and s^2 .

The relay O has the two fixed contacts o^1 and o^2 arranged to be bridged by the switch or contact o^3 , which carries a core o^5 controlled by the winding o^4 . The contact o^1 is connected through the winding o^4 and the wire 1 to the positive side of the switch S and the contact o^2 is connected through the winding s^3 of the switch S to the wire 4. The winding s^3 controls the core s^5 connected to the switch arm s^4 so as to cause the contacts s^1 and s^2 to be closed when the winding s^3 lifts the said core.

If the switch B is closed by moving its arm b^4 to the left so that brush b^3 spans the contacts b' and b^2 , a circuit is established through the magnet winding M as follows: from the positive side of the switch S through the wires

1 and 2, the contacts b' , b^3 , and b^2 , the wire 3, the resistance R, the winding M and the wire 4 to the negative side of the switch S. In this circuit the winding M is in series with the resistance R and connects both across the line. If now the controller or switch C is closed, current is established through the motor circuit as follows: from the positive side of the switch S, through the wire 1, the relay coil o^4 , the switch C, the armature A and the field F to the negative side of the switch S. As stated before, the current through the motor at starting is large. It, therefore, energizes the relay coil o^4 sufficiently to cause the core s^5 to rise so that switch o^3 bridges the contacts o' and o^2 , thus establishing a circuit as follows:—from the positive side of the switch S through the wire 1, the coil o^4 , the contacts o' , o^3 , and o^2 , the coil s^3 of the switch S', and the wire 4 to the negative side of the switch S. This circuit energizes the coil s^3 so as to cause it to raise the core s^5 and close the contacts s' and s^2 . The closing of these two contacts shunts the resistance R with the arm s^4 of the switch S'. This shunt permits a larger current to flow through the magnet M, the circuit now being as follows: from the positive side of the switch S, through the wire 1, the wire 2, the contacts b' , b^3 , and b^2 , the wire 3, the arm s^4 , the contacts s' and s^2 , the magnet winding M, and the wire 4 to the negative side of a switch S.

By the proper adjustment of the relay O, the core s^5 may be caused to remain in its upward position until the hoisting motor has lifted the magnet and the load from the pile, and all the moving parts brought up to speed. When this has occurred, the current through the hoisting motor and the relay coil o^4 has gradually decreased until the relay is no longer able to hold up its core s^5 . When the core drops, the circuit of the switch coil s^3 of switch S' is opened at the switch o^3 and the arm s^4 opens the contacts s' and s^2 , which re-inserts the resistance R in series with the magnet winding M and decreases the current through the magnet, thus reducing its heating. If the resistance R is properly proportioned, the current in the winding may be

materially reduced without causing the magnet to drop any of its load.

When the load has been transferred to the desired position, it may be released from the magnet by moving the arm b^4 of the switch B to the right so that the brush b^3 leaves contact with the contacts b' and b^2 .

I claim—

1. In a controlling system for lifting magnets, an electric motor, a lifting-magnet winding in shunt with the motor circuit, and means for automatically inserting resistance in series with the said winding. 60

2. In a controlling system for lifting magnets, an electric motor, a lifting-magnet winding, and means for automatically decreasing the current in the said winding after the said motor has been accelerated. 65

3. In a controlling system for lifting magnets, an electric motor, a lifting-magnet winding in shunt with the motor circuit, and means governed by the current in the motor circuit for automatically controlling the amount of current flowing in the said winding. 70

4. In a controlling system for lifting magnets, a lifting-magnet winding, a resistance in series with said winding, an electro-magnet, contacts controlled by the electro-magnet to shunt said resistance, an electric motor, a relay winding in the motor circuit, contacts controlled by the relay winding and controlling said electro-magnet, and a switch to close the circuit of the magnet winding. 75

5. In a controlling system for lifting magnets, a lifting-magnet winding, a resistance in series with the said winding, an electro-magnet, contacts controlled by said electro-magnet to shunt the resistance, an electric motor, a relay winding in the motor circuit, 80 means actuated by said relay winding during the rush of current in the motor circuit before the motor has been accelerated to short-circuit said resistance. 85

Signed at Cleveland, Ohio, this sixth day of April, A. D. 1908.
